UNITED STATES PATENT OFFICE.

ALFRED H. OELKERS, OF SPRINGFIELD, MISSOURI.

WATER COLUMN FOR LOCOMOTIVES.

Application filed January 14, 1925. Serial No. 2,338.

To all whom it may concern:

Be it known that I, ALFRED H. OELKERS, a citizen of the United States, and a resident of Springfield, in the county of Greene and State of Missouri, United States of America, have invented a new and Improved Water Column for Locomotives, of which the following is a full, clear, and exact description.

10 This invention relates to boilers for locomotives and is more particularly directed to a water column applicable to such boilers.

15 An object of the invention is the provision of a water column for boilers for locomotives which is of such a character that it will be universally applicable to different sizes and types of locomotives.

20 Another object of the invention is the provision of a water column which will permit a complete cleaning of the passages leading into the boiler and the body of the water column.

25 A further object of the invention is the provision of a water column having such a safe and strong connection with a boiler that in case of an accident the device will be distorted without rupture, thereby preventing scalding of the operator of the 30 locomotive.

This invention will be best understood from a consideration of the following detailed description in view of the accompanying drawings forming part of the specification; nevertheless it is to be understood that the invention is not confined to the disclosure, being susceptible of such changes and modifications which shall define no material departure from the salient features 40 of the invention as expressed in the appended claims.

Figure 1 is a view in elevation of my improved water column connected to a locomotive boiler.

45 Fig. 2 is an end view of the water column with the boiler partly in section.

Fig. 3 is a vertical section of the lower connection between the water column and a locomotive boiler.

50 Fig. 4 is a top plan view, partly in section of the device shown in Fig. 3.

Fig. 5 is a front view in elevation of the same.

55 Fig. 6 is a modified form of the device shown in Fig. 3.

Referring more particularly to the draw-

ings, 1 designates a locomotive boiler having a steam dome 2 to which a water column 3 is connected by means of a tubing 4. The tubing 4 is connected to the column 3 by 60 a union 5 and to a threaded nipple 6 by a union 7, the nipple 6 being threaded into a perforation in the boiler.

The column 3 is provided with threaded 65 perforations adjacent its upper and lower ends into which are screwed nipples 8. The upper nipple 8 connects the water column 3 with a valve 9, while the lower nipple is connected to a conduit 10 and a glass cylinder 11. The flow of the water into the glass cylinder is controlled at its lower end by a valve 12, while the communication is controlled between the upper end of the glass cylinder and the water column 3 by the valve 9. Gage cocks 13 are screwed into 70 threaded openings in the wall of the column 3 and the construction of said column is of the usual type. The fixtures included with the glass cylinder 11 are of the usual type 75 and need no further explanation.

80 Projecting outwardly from the body member 3 are a pair of ears 14 adapted to be connected by a pin 15 to a pair of ears 16 on the body of the boiler 1. The lower end of the body member 3 is provided with an opening into which is adapted to be screwed a nipple 17, the lower end of the nipple being threaded into an opening 18 formed at the upper end of a joint or connecting device generally designated by the numeral 85 19. The connecting device 19 is provided with a central passage 20. Threaded openings are in communication with the passage 20. Into said openings are respectively screwed the threaded plugs 21 and 22. 90 These plugs are provided for draining and 95 cleaning the pipe connection when desired. An offset conduit 23 is in communication with the conduit 20 and has its lower end internally threaded as shown at 24 to receive a pipe connection 25. Diametrically opposite the plug 21 is provided a conduit 26 in open communication with the passage 20. The free end of conduit 26 is rounded as shown at 27 to be received within a 100 socket 28 on the outer end of a threaded nipple 29. This nipple, as shown in Fig. 2, is screwed into a threaded opening in the wall of the boiler.

105 The outer end of the nipple 29 is provided with a shoulder 30 adapted to be engaged by a plate 31 which has a central perforation 110

adapted to receive the nipple 29. The plate is provided with pairs of spaced ears 32 between which are received bolts 33. The head of each bolt engages said ears, while the other end is inserted through perforations in flanges 34 projecting laterally from the connecting device 19. A nut as is usual locks the bolts to the cooperating flanges 34 and the ears 32.

10 The flanges 34 as it appears from Figures 4 and 5 are formed integrally with the connecting member 19.

15 In the modified form of the connecting device shown in Fig. 6, the body member 19^a is provided with a horizontal connection 35, into which is adapted to be screwed the pipe 25. In other words the essential difference between the device shown in Fig. 6 and that shown in Figs. 3 to 5 inclusive is 20 the fact that pipe 35 is a straight connection, while the conduit 23 is bent downwardly for disposing the vertical contact 25 in spaced relation with the conduit 20 of the connecting device 19.

25 It will be seen by this construction that any boiler may be fitted with a water column by varying the lengths of the nipples 17 as may be required. The construction of the nipple 29 and the ball and socket connection 30 between said nipple and the body member 19 of the connecting device permits the water column to be distorted without rupture and thus eliminating the danger of scalding of the operators of the locomotives.

35 I claim:

1. In a locomotive boiler having a water column, a means for connecting the water

column to said boiler comprising a hollow body having a threaded opening, a pipe member screwed into the opening and 40 adapted to be connected to the water column, said hollow body being provided with attaching ears having perforations, a nipple screwed into the boiler and having a flanged outer end, a perforated plate received by the nipple and engaging the flange, said plate being provided with pairs of spaced ears, and bolts located between each pair of spaced ears and also passed through the perforations in the flanges on 45 the body member for locking the body member to the nipple.

2. In a locomotive boiler having a water column, means for connecting the water column to said boiler and comprising a joint 55 in the form of a hollow body member provided with diametrically disposed horizontal passages and aligned vertical passages at the opposite end of the joint, a nipple threaded into the upper vertical passage, 60 a plug closing the other vertical passage, a plug for closing one of the horizontal passages, a hollow boss formed integrally with the joint and aligned with the other horizontal passage, a conduit projecting outwardly and downwardly from the joint adjacent the lower horizontal passage and having an internally threaded opening to receive a threaded pipe connection, means on 65 the joint for aiding in alining the pipe connection in sealed relation with the hollow boss.

ALFRED H. OELKERS.
